DISPLAY PACKAGE FOR DRILLS
OR THE LIKERichard E. Puckett, Chicago, Ill., assignor to
United Drill and Tool Corporation, Chicago, Ill.,
a corporation of Michigan

Application September 25, 1947, Serial No. 776,014

5 Claims. (Cl. 206—78)

1

The present invention relates to display packages that are especially constructed and arranged to receive elongated drills or the like.

Display packages that have been employed heretofore for drills and other rather heavy cutting tools have been unsatisfactory from several standpoints. In the first place, the construction of such drill packages has not been sufficiently substantial; and incident to shipping or handling thereof, frequently a drill becomes unattached from its mounting and cuts through the wall of the package to the exterior. Not only are these broken drill packages dangerous to handle, but all of the contained drills are exposed directly to contact by the handler, and also to the atmosphere, causing rusting and other damage to the contained drills. Moreover, in handling these drill packages, often the labels carried thereby are injured and instructions and other information printed on the labels are obliterated, whereby the marketability of the drill packages and the contained drills is impaired. Further, such drill packages have not afforded an attractive and artistic display of the contained drills, while permitting ready visual inspection thereof without breaking the packages.

Accordingly, it is a general object of the present invention to provide an improved display package that is adapted securely to mount in place one or more contained drills or the like and to afford an attractive display of the drills while permitting ready visual inspection thereof without breaking the package.

Another object of the invention is to provide a display package of the character described that further embodies an improved arrangement for preventing damage or injury to the label carried thereby.

A further object of the invention is to provide a display package for elongated drills or the like, that comprises an improved arrangement for preventing the contained drills from damaging the wall of the package.

A further object of the invention is to provide a drill package of improved construction and arrangement and of attractive appearance enhancing the marketability thereof.

A still further object of the invention is to provide a drill display package of substantial construction; whereby the display package constitutes a chest that may be employed for housing the drills after purchase by the ultimate user.

Further features of the invention pertain to the particular arrangement of the elements of the display package, whereby the above outlined

2

and additional operating features thereof are attained.

The invention, both as to its organization and method of operation, together with further objects and advantages thereof, will best be understood by reference to the following specification taken in connection with the accompanying drawings, in which Figure 1 is a front view of a display package for drills or the like embodying the present invention; Fig. 2 is a side view of the display package shown in Fig. 1; Fig. 3 is a rear view of the display package shown in Figs. 1 and 2; Fig. 4 is an enlarged fragmentary front view of the display package shown in Figs. 1, 2 and 3; Fig. 5 is a front view, partly broken away, of a modified form of display package embodying the present invention; Fig. 6 is a side view of the display package shown in Fig. 5; Fig. 7 is a rear view of the display package shown in Figs. 5 and 6; Fig. 8 is a front view, partly broken away, of another modified form of a display package embodying the present invention; Fig. 9 is a side view of the display package shown in Fig. 8; Fig. 10 is a rear view of the display package shown in Figs. 8 and 9; Fig. 11 is a front view, partly broken away, of a further modified form of display package embodying the present invention; Fig. 12 is a side view of the display package shown in Fig. 11; and Fig. 13 is a rear view of the display package shown in Figs. 11 and 12.

Referring now more particularly to Figs. 1 to 4, inclusive, of the drawings, the drill display package 100 there illustrated, and embodying the features of the present invention, is substantially rectangular in plan, and comprises a relatively thick, stiff body element 110 formed of laminated cardboard or the like, and having a plurality of laterally spaced apart elongated openings 111 formed therethrough. The openings 111 formed through the body element 110 are of graduated sizes, increasing both in width and length from left to right, in order to receive a corresponding plurality of elongated articles in the form of drills 112 of graduated sizes and constituting a matched set to be packaged and displayed; the thickness of the body element 110 being slightly greater than the diameter of the largest drill 112 in the matched set in order to accommodate housing thereof. Preferably, the openings 111 formed in the body element 110 are inclined slightly upwardly and to the right in order to enhance the artistic display of the matched set of drills 112; the points of the drills 112 being positioned adjacent to the bottom of

the openings 111 formed in the body element 110 to present a uniform and attractive arrangement.

Also the display package 100 comprises a front inner cover 113 substantially conforming to the outline of the body element 110 and formed of a relatively thin paper; preferably a coated tag stock. The front inner cover 113 is secured to the front surface of the body element 110 utilizing cement; whereby the adjacent surfaces of the body element 110 and the front cover 113 are bonded and sealed together. The front surface of the front inner cover 113 bears a label which is preferably in printed form, displaying the trade-mark, the drill sizes, instructions concerning the use of the drills and other art work or the like. Likewise, the front inner cover 113 has a plurality of laterally spaced apart elongated holes 114 formed therethrough and arranged in substantial registry with the openings 111 formed through the body element 110. Each of the elongated holes 114 formed through the front inner cover 113 is slightly shorter than the corresponding registering elongated opening 111 formed through the body element 110; whereby top and bottom integral projections or tabs 115T and 115B are formed on the front inner cover 113 and overlying the respective ends of the drills 112.

Further the display package 100 comprises a continuous front outer cover 116 substantially conforming to the outline of the body element 110 and the front inner cover 113 and formed of transparent material of intermediate thickness. Preferably, the front outer cover 116 is formed of a heavy grade of plastic sheet, such for example, as cellulose acetate. The front outer cover 116 is secured to the front surface of the front inner cover 113 utilizing cement; whereby the adjacent surfaces of the front outer cover 116 and the front inner cover 113 are bonded and sealed together. Accordingly, the front outer cover 116 not only closes the front of the openings 111 formed through the front inner cover 113 and the front of the openings 111 formed through the body element 110, but it also protects the label, etc., borne by the front surface of the front inner cover 113 against damage or injury.

Finally, the display package 100 comprises a continuous back cover 117 formed of strong material of intermediate thickness and secured to the back surface of the body element 110 to close the back of the openings 111 formed therethrough. For example, the back cover 117 may comprise a heavy paper sealer of the gummed variety; whereby the adjacent surfaces of the back cover 117 and the body element 110 are sealed together.

In the manufacture of the display package 100 the body element 110 is suitably formed; the coated tag stock is suitably printed to produce the required label and then die cut to form the front inner cover 113; and the front outer cover 116 is formed from a suitable sheet of cellulose acetate stock. The front outer cover 116 is then cemented to the front inner cover 113; and the composite front cover is secured to the front surface of the body element 110 utilizing cement and employing the process commonly known as "lamination under heat"; whereupon the display package 100 thus produced is then stored for subsequent use. Later, the partially finished display package 100 described above is taken from storage and the matched set of drills 112 is loaded into the openings 111 formed in the body element 110 from the back; whereby the top and bottom tabs 115T and 115B formed on the front inner cover

113 engage the respective ends of the drills 112 disposed in the openings 111 formed through the body element 110 preventing these portions of the drills 112 from engaging the overlying portions of the front outer cover 116. This arrangement of the tabs 115T and 115B is very advantageous as the front inner cover 113 being formed of relatively soft paper prevents the sharp edges of the drills 112 from engaging the adjacent overlying portions of the front outer cover 116. While the front outer cover 116 is very strong and tough, being formed of a heavy grade of cellulose acetate, the tabs mentioned have been found to be most advantageous as the edges mentioned of the drills 112, particularly the cutting edges thereof, have a tendency to scratch a cellulose sheet upon direct engagement. Thus the tabs 115T and 115B carried by the front inner cover 113 prevent direct engagement between the drills 112 and the front outer cover 116 and the consequent scratching and damage thereto.

After the drills 112 have been loaded through the back of the openings 111 formed through the body element 110, cotton, soft paper or the like may be placed behind the smaller drills 112 in order to take up the additional space as a consequence of the substantially uniform thickness of the body element 110; thereby preventing the smaller drills 112 from shifting about in the openings 111 formed in the body element 110. Ultimately, the back cover 117 in the form of a piece of gummed sealer or paper may be torn from a roll, moistened, and then applied to the back surface of the body element 110 in order to complete the display package 100 and securely to retain the packaged drills 112 therein.

The display package 100 not only affords a convenient and attractive shipping and display package for the drills 112, but it also constitutes a substantially air tight housing therefor preventing moisture and other elements from damaging the packaged drills 112 before they are sold to the ultimate user.

Referring now more particularly to Figs. 5 to 7 inclusive, the modified form of drill display package 200 there illustrated, and embodying the features of the present invention, is of the same basic construction and arrangement as the display package 100 described in detail above. Moreover, in the display package 200 the selection of the materials of the component elements thereof, the method of assembling the elements thereof, the method of loading the drills therewith and the final sealing and completion thereof are based upon the same considerations described in connection with the display package 100. Finally corresponding reference characters have been employed in the drawings to designate corresponding elements of the display packages 100 and 200.

Briefly, the display package 200 comprises a body element 210, a front inner cover 213, a front outer cover 216 and a rear cover 217, the body element 210 having a single elongated opening 211 formed therethrough adapted to receive a plurality of elongated articles in the form of a matched set of drills 212 of graduated sizes, and the front inner cover 213 bearing a label or the like and having a single elongated hole 214 formed therethrough and arranged in substantial registry with the opening 211 formed through the body element 210 and carrying upper and lower tabs 215T and 215B overlying the respective ends of the drills 212. Also in the display package 200 pairs of aligned abutments or notches 211a are arranged in the upper and lower edges of the

opening 211 formed through the body element 210 in order to receive and to position the corresponding ends of the packaged drills 212 and to retain them in laterally spaced apart relation.

Referring now more particularly to Figs. 8 to 10, inclusive, the other modified form of drill display package 300 there illustrated, and embodying the features of the present invention, is of the same basic construction and arrangement as the display package 100 described in detail above. Moreover, in the display package 300 the selection of the materials of the component elements thereof, the method of assembling the elements thereof, the method of loading the drills thereto and the final sealing and completion thereof are based upon the same considerations described in connection with the display package 100. Finally corresponding reference characters have been employed in the drawings to designate corresponding elements of the display packages 100 and 300.

Briefly, the display package 300 comprises a body element 310, a front inner cover 313, a front outer cover 316 and a rear cover 317, the body element 310 having a single elongated opening 311 formed therethrough adapted to receive a plurality of elongated articles in the form of a matched set of drills 312 of graduated sizes, and the front inner cover 313 bearing a label or the like and having a single elongated hole 314 formed therethrough and arranged in substantial registry with the opening 311 formed through the body element 310 and carrying upper and lower tabs 315T and 315B overlying the respective ends of the drills 312. Also in the display package 300 the dimensions of the opening 311 formed through the body element 310 are fixed in order nicely to receive the matched set of drills 312; whereby it is unnecessary to count the individual drills 312 as they are loaded into the opening 311, since the opening 311 will accommodate when filled precisely the fixed number and sizes of the matched set of drills 312.

Referring now more particularly to Figs. 11 to 13, inclusive, the further modified form of drill display package 400 there illustrated, and embodying the features of the present invention, is of the same basic construction and arrangement as the display package 100 described in detail above. Moreover, in the display package 400 the selection of the materials of the component elements thereof, the method of assembling the elements thereof, the method of loading the drills thereto and the final sealing and completion thereof are based upon the same considerations described in connection with the display package 100. Finally corresponding reference characters have been employed in the drawings to designate corresponding elements of the display packages 100 and 400.

Briefly, the display package 400 comprises a body element 410, a front inner cover 413, a front outer cover 416 and a rear cover 417, the body element 410 having a single elongated opening 411 formed therethrough adapted to receive a plurality of elongated articles in the form of drills 412, and the front inner cover 413 bearing a label or the like and having a single elongated hole 414 formed therethrough and arranged in substantial registry with the opening 411 formed through the body element 410 and carrying upper and lower tabs 415T and 415B overlying the respective ends of the drills 412. Also in the display package 400 the dimensions of the opening 411 formed through the body element 410 are fixed in

order nicely to receive precisely one dozen of the drills 412 of a given size; whereby it is unnecessary to count the individual drills 412 as they are loaded into the opening 411, since the opening 411 will accommodate when filled precisely one dozen of the drills 412 of the given size. Further in the display package 400, the rear cover 417 is in the form of a door arranged in the rear of the opening 411 formed through the body element 410, and is preferably made of relatively thin cardboard or the like instead of gummed sealer or paper as in the display package 100. Specifically, the door 417 is arranged in the back of the opening 411 formed through the body element 410 and is hinged in place by a hinge 417a in the form of a strip of gummed paper or "Scotch tape" and is provided with a tab 417b in the form of a strip of gummed paper or "Scotch tape" in order to retain it in its closed position. Accordingly, the door 417 is adapted to close the back of the openings 411 formed through the body element 410 and also to afford access to the packaged drills 412. When access to the packaged drills 412 is desired, the tab 417b may be pulled up from the back of the body element 410 permitting the door 417 to be hinged away from the back of the opening 411 formed through the body element 410 about the hinge 417a. Subsequently, the door 417 may be returned to its closed position and again secured therein by pressing the tab 417b again into engagement with the back of the body element 410.

In view of the foregoing, it is apparent that there has been provided a display package for drills or the like, that is of improved construction and arrangement; whereby the drills are attractively displayed and are securely mounted in place and housed out of contact with the atmosphere or other injurious elements. Also the display package permits ready inspection of the drills without actual handling thereof, and preserves the label or other instructions printed on the front inner cover thereof that might otherwise be damaged or injured as a consequence of handling of the package. Furthermore, since the display package is of substantial construction, it constitutes a chest that may be employed for housing the drills after purchase by the ultimate user.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. A drill display package comprising a body element formed of stiff material having an opening therethrough forming a pocket therein, a drill positioned in said pocket, a front inner cover formed of soft material secured and sealed to the front surface of said body element and having a hole therethrough in substantial registry with said opening, at least one dimension of said hole being smaller than the corresponding dimension of said opening to provide one or more integral projections on said front inner cover overlying corresponding one or more portions of the packaged drill, a front outer cover formed of hard transparent material secured and sealed to the front surface of said front inner cover to close the front of said opening, said projection or projections preventing the corresponding portion or portions of the packaged drill from en-

gaging directly said front outer cover, and a back cover secured to the back surface of said body element to close the back of said opening.

2. A drill display package comprising a body element formed of stiff material having a plurality of spaced apart elongated openings of graduated sizes therethrough forming pockets therein, a corresponding plurality of drills of graduated sizes constituting a matched set positioned in said pockets, a front inner cover formed of soft material secured and sealed to the front surface of said body element and having a corresponding plurality of elongated holes of graduated sizes therethrough substantially registering with respective ones of said openings and bearing a label or the like, said holes being somewhat shorter than said openings to provide top and bottom projections on said front inner cover overlying the corresponding ends of the packaged drills, a continuous front outer cover formed of hard transparent material secured and sealed to the front surface of said front inner cover to close the front of said openings and to protect said label against damage or injury, said top and bottom projections preventing the corresponding ends of the packaged drills from engaging directly said front outer cover, and a continuous back cover secured to the back surface of said body element to close the back of said openings.

3. A drill display package comprising a body element formed of stiff material having an elongated opening therethrough forming a pocket therein of fixed dimensions, a fixed number of drills nicely positioned in said pocket, whereby it is unnecessary to count the drills as they are positioned in said pocket since said pocket will accommodate when filled precisely the fixed number thereof, a front inner cover formed of soft material secured and sealed to the front surface of said body element and having an elongated hole therethrough substantially registering with said opening and bearing a label or the like, said hole being somewhat shorter than said opening to provide top and bottom projections on said front inner cover overlying the corresponding ends of the packaged drills, a front outer cover formed of hard transparent material secured and sealed to the front surface of said front inner cover to close the front of said opening and to protect said label against damage or injury, said top and bottom projections preventing the corresponding ends of the packaged drills from engaging directly said front outer cover, and a back cover secured to the back surface of said body element to close the back of said opening.

4. A drill display package comprising a body element formed of stiff material having an elongated opening therethrough forming a pocket therein of fixed dimensions, a fixed number of drills of graduated sizes constituting a matched set nicely positioned in said pocket, whereby it is unnecessary to count the drills of the matched set as they are positioned in said pocket since said pocket will accommodate when filled pre-

cisely the fixed number thereof constituting the matched set, the top and bottom edges of said opening being provided with abutments receiving and positioning the corresponding ends of the packaged drills, a front inner cover formed of soft material secured and sealed to the front surface of said body element and having an elongated hole therethrough substantially registering with said opening and bearing a label or the like, said hole being somewhat shorter than said opening to provide top and bottom projections on said front inner cover overlying the corresponding ends of the packaged drills, a front outer cover formed of hard transparent material secured and sealed to the front surface of said front inner cover to close the front of said opening and to protect said label against damage or injury, said top and bottom projections preventing the corresponding ends of the packaged drills from engaging directly said front outer cover, and a back cover secured to the back surface of said body element to close the back of said opening.

5. A drill display package comprising a body element formed of stiff material having an elongated opening therethrough forming a pocket therein of fixed dimensions, a fixed number of drills nicely positioned in said pocket, whereby it is unnecessary to count the drills as they are positioned in said pocket since said pocket will accommodate when filled precisely the fixed number thereof, a front inner cover formed of soft material secured and sealed to the front surface of said body element and having an elongated hole therethrough substantially registering with said opening and bearing a label or the like, said hole being somewhat shorter than said opening to provide top and bottom projections on said front inner cover overlying the corresponding ends of the packaged drills, a front outer cover formed of hard transparent material secured and sealed to the front surface of said front inner cover to close the front of said opening and to protect said label against damage or injury, said top and bottom projections preventing the corresponding ends of the packaged drills from engaging directly said front outer cover, and a hinged door carried by said body element and cooperating with the back of said opening, whereby said door is adapted to close said opening and also to afford access to the packaged drills.
